INDEXING DEVICE FOR HOME RECORDERS

Gilbert G. Brown, Philadelphia, Pa., assignor to
Philco Radio and Television Corporation, Philadelphia, Pa., a corporation of Delaware

Application January 14, 1942, Serial No. 426,781

18 Claims.

(Cl. 274—9)

This invention relates to phonograph apparatus, and more especially to means for indexing the stylus of such apparatus in proper starting position with respect to the peripheral edge of a six and one-half, eight, or ten inch blank disc, for example. The invention is illustrated with and is particularly useful in recording apparatus, and these various sizes are most commonly used in making home recordings. However, it will be understood that the indexing means of the present invention is adapted for use with records of one size only, or of any predetermined range of sizes, without departing from the spirit of the invention; and the invention might be modified for use with reproducing apparatus if such should be desired.

In modern home-recording apparatus for phonographs, the stylus is usually located on the under side of the cutting arm of the phonograph in a position obscure to the person operating the apparatus, due to the width of the arm, or the position of the arm in the cabinet or both. Thus, considerable difficulty has been encountered in placing the sharp point of the stylus on the record in proper relation to the peripheral edge thereof for obtaining the fullest benefit of the normal capacity of the disc without danger of the stylus being placed on the rotating turntable of the phonograph, beyond the edge of the record, or by its being placed on the record so close to the edge thereof that the stylus may accidentally slip off the record onto the turntable or be engaged by the edge of the rotating record, which, in any case usually ruins the stylus for immediate use.

In the case of home-recording apparatus operable in conjunction with radio receivers adapted for recording broadcasts picked up by the radio, such as speeches by prominent world-famous people, vocal and instrumental programs, etc., the opportunity to make a complete recording is frequently lost by the stylus being improperly placed on the record at the beginning of that portion of the broadcast intended to be recorded.

The primary object of the present invention is to provide a simple, efficient, inexpensive indexing mechanism for phonograph apparatus, by which the stylus will be properly positioned on a disc, i. e., approximately three-sixteenths of an inch inwardly from the peripheral edge of the record, under control of the operator's sense of feeling, rather than by sense of sight.

Another object of the present invention is to provide mechanism of the kind noted, by which the stylus may be properly positioned on any one of a number of records of different diameters, re-

spectively, or on the face of a single record at any one of a number of different points radially spaced with respect to the axis of rotation of the record.

Still another object of the invention is to provide an indexing means, which will function in conjunction with the driving mechanism for the stylus-supporting or "cutting" arm, whereby the number of working parts, and, consequently, the cost of manufacture, will be reduced to a minimum.

Still another object of the invention is to provide an indexing means which will automatically become effective when the stylus-supporting arm is lifted from a normal, inoperative position of rest and is swung across the record into starting position, and which will be automatically rendered ineffective when the arm is lowered to bring the stylus into engagement with the record at the indexed starting point, so as to avoid interference with the normal functioning of the stylus during its period of engagement with the record.

The indexing means of the present invention is illustrated, in accordance with the aforesaid objects, in conjunction with a special stylus-driving and controlling mechanism forming the subject matter of the present assignee's copending application of Ingo L. Stephan, Serial No. 425,934, filed January 7, 1942.

The construction and operation of the indexing means of the present invention will be fully disclosed hereinafter, reference being had to the accompanying drawings, of which:

Fig. 1 is a vertical sectional elevation of the device as applied to a conventional form of phonograph equipped with a stylus-controlling means of the aforesaid kind;

Fig. 2 is a perspective view, looking upwardly from underneath, of the indexing and driving means shown in Fig. 1; and

Fig. 3 is a sectional perspective view, from above, showing the indexing means in its relation to the driving means during the operation of the recording apparatus.

As shown in the present drawings, the base member of a conventional phonograph is illustrated at 10; the turntable at 11; the cutting stylus at 15 as being carried by an electro-acoustic transducer or cartridge 14, which, in turn, is supported by the stylus-controlling arm 13.

The stylus arm 13 is pivoted at 12 to a collar 18 which is secured to the upper end of a tubular stud shaft 17. The vertical shaft 17 is rotatably mounted in a bearing 16 which is secured to the base member 10. Secured to the lower end of the

shaft 17 is a stylus-driving arm 18, which is provided with a segmental extension 48, the outer arcuate edge of which is adapted for frictional driving engagement with a driving pinion 38 formed on a hub element 27. The hub element 27 is rotatably mounted on a pivot stud 28, which is supported by a swing plate 23.

The swing plate 23 is pivoted at 22 to a sub-base element 20, which is supported from the main base 19 by the bearing 16 and screws 21. The plate 23 is adapted to be swung about its pivot, under the influence of a spring 25 to maintain firm frictional driving contact between the pinion 38 and the arcuate edge of the segment 48 of the stylus-driving arm 18.

The hub 27, of which the pinion 38 forms an integral part, is adapted to be intermittently rotated, through a ratchet wheel 28 secured to the upper end of the hub element 27, by a spring biased pawl 35 which is pivotally mounted on an actuating lever 31. The lever 31 is loosely mounted on a stepped portion of the hub 27 for free relative oscillation with respect thereto.

The actuating lever 31 is oscillated normally, during a recording operation, by a cam or eccentric disc 34 attached to the turntable 11, for concurrent rotation therewith and with a blank disc record D seated flatly on the turntable. The cam disc 34 operates against a cam follower 33 which is rotatably mounted on the outer end of the actuating lever 31, a spring 37 normally maintaining contact therebetween during the recording operation.

The foregoing description applies solely to the driving means for the stylus arm 18 and serves as a basis for the description of the construction and operation of the indexing means which forms the subject matter of the present invention.

As shown in Fig. 1, a bracket 58 is loosely mounted on the lower end of the vertical tubular shaft 17, below the driving arm 18. Pivoted at 51 to the bracket 58 is a bell-crank lever 52. The upper edge of one arm 53 of the bell-crank lever 52 is adapted to be engaged by the lower rounded end of a push rod 55, which is mounted within the bore of the tubular shaft 17. The upper rounded end of the push rod 55 is adapted to be engaged by the head of an adjustable abutment screw 54, carried by the stylus arm 18, in axial alignment with the shaft 17 which affords horizontal swinging movement of the arm 18, and in laterally offset relation to the pivot 12 which affords vertical swinging movement of the arm 18.

The second arm 56 of the bell-crank lever 52 is provided with one, or two, laterally-extending pins 57 which fit within longitudinally-elongated slots or recesses 58 formed in a longitudinally-shiftable indexing bar 60. A spring 59, stretched between and having its opposite ends, respectively, secured to a part of the bracket 58 and a part of the indexing bar member 60, tends to maintain the indexing bar in a forward position with respect to the axis of the shaft 17.

The outer or forward end of the indexing bar 60 is bifurcated at 61 to span a circular portion 62, of reduced diameter, of the hub 27, within an annular groove 63 formed in said hub member.

Spaced inwardly from its bifurcated end 61, the bar 60 is provided with a vertical bearing 63a for slidably supporting an axially-movable indexing pin 65. The head 64 of the indexing pin 65 is engaged by one end of a flat spring 66, the opposite end of which is rigidly secured to the

indexing bar 60, for exerting an upward pressure on the indexing pin 65.

The upper end of the indexing pin 65 is adapted to enter one of a plurality of indexing apertures 67, 68 or 69, formed in the driving arm 18 or its segmental extension 48.

The bracket 58 is provided with a pair of laterally-spaced aligning lugs or fingers 70, 71 between which the bar 60 slides. A block or plate 71 of fibre is disposed between the posts or fingers 70, 71, above the bar 60 to provide a smooth bearing surface for said bar during longitudinal shifting movement thereof.

From the foregoing description, taken in conjunction with the illustrations of the drawings, it will be clear that, when starting a recording on either a six and one-half, eight or ten inch record, with the stylus arm 18 in a position outwardly beyond the periphery of the turntable 11, and with the driving sector 48 in the position shown in Fig. 2, wherein the indexing apertures 67, 68 and 69 are remotely positioned with respect to the indexing pin 65, the first operation is to raise the stylus arm 18 from its normal position of rest, wherein an abutment 73 bears on an abutment screw 74, to the manual swinging position shown in Fig. 1.

When the stylus-supporting arm 18 is in its raised position, the push rod 55 is in its uppermost position, allowing the bar 60 to assume its extreme forward position, with the indexing pin 65 located against the under side of the driving arm 18, in a position radially disposed with respect to the axis of the shaft 17, which corresponds to the radius of the arc, swung from the center of the shaft 17, on which the indexing indentations or openings 67, 68 and 69 are formed in the driving arm 18.

The stylus-supporting arm 18 is then manually swung inwardly over the turntable 11 (carrying with it the indexing sector 48) to place the stylus 18 in proper position on the record D adjacent the peripheral edge of the record, which may be of a six and one-half, eight, or ten inch diameter, as desired. If, for example, a ten inch record is to be made, the manual swinging of the stylus arm 18 will be stopped, or further inward movement thereof resisted to an extent to be felt by the person swinging the arm 18, by reason of the indexing opening 67 in sector 48 of the driving arm 18 being the first of the index spots 67, 68 and 69 to be brought into alignment with the indexing pin 65. The upper rounded end of the indexing pin 65 will be projected, by the spring 66, into said index opening 67. The relative positioning of the aperture 67 is such that the stylus will then be in correct position with respect to the peripheral edge of the ten inch disc D for beginning the formation of a continuously spiral sound groove in the face of the record D.

The pressure of the spring finger 66 is such that the operator will be aware of a definite resistance to further swinging movement of the stylus arm 18 and thus realize that the first indexing position, for a ten inch record, has been reached.

When the pin 65 registers with the hole 67, with the ten inch record on the turntable 11, the stylus arm 18 is then lowered. In so doing, the abutment 54, carried by the arm 18, forces the push rod 55 downwardly, against the action of the spring 59, and rocks the bell-crank lever 52 about its pivot 51. Rocking of the bell-crank lever in this manner moves the indexing bar 60

inwardly, i. e., toward the shaft 17, against the action of the spring 59, which causes the indexing pin 65 to be moved out of the indexing aperture 67 to a position inwardly beyond the radius on which the openings 67, 68 and 69 are formed, as clearly shown in Fig. 3, the bifurcated or forked end 61 of the bar 60 permitting such inward longitudinal shifting of the indexing bar 60.

When the ten inch recording is completed, the arm 13 is again raised to swing the stylus outwardly beyond the peripheral edge of the record D, the elements reassuming the general relationship shown in Fig. 1 at the start of the outward movement of the stylus-supporting arm 13.

When the stylus arm 13 is in its extreme outward and lowered position of rest, the bearing pad 73 on the stylus-supporting arm 13 bears against the rest 74 which is carried by the collar 18, and which may be adjusted to such an elevation as to prevent the point of the stylus 15 from striking or resting on the base 16 under such circumstances.

If an eight or a six and one-half inch record is to be recorded, the same operations, as previously noted, are followed through. However, when the stylus comes into position for a ten inch record, the indexing pin 65 would again enter the lower end of the indexing aperture 67, but, if an eight inch record, for example, is to be made, continued movement inwardly of the arm 13 will cause the index pin 65 to ride out of the ten inch indexing aperture 67 into contact with the underside of the arm 13, to bear against the under side of the arm, on the arc of the apertures 67, 68 and 69, until the indexing pin 65 snaps into the eight inch indexing aperture 68.

If a six and one-half inch record is to be recorded, further continued swinging of the arm 13 inwardly will cause the pin 65 to ride out of the eight inch indexing aperture 68 and along the under side of the arm 13, into the six and one-half inch indexing aperture 69. Then, as the arm 13 is lowered about its pivot 12, to bring the stylus 15 into contact with the record D, the bar 60 will be shifted inwardly from the position shown in Fig. 1 to that shown in Fig. 3, wherein the indexing pin 65 is drawn out of aperture 68 to a position inwardly with respect thereto, while bearing on the under side of the arm 13. As the recording is being made, the pin 65 rides idly against the under side of the arm 13 past the indexing openings 69, 68, 67, successively, on an arc of smaller radius than that on which the indexing apertures are arranged, thus preventing any interference with the recording operation.

While the invention has been described in connection with the indexing of the stylus on records of different diameters, respectively, the principles of the invention are equally applicable to indexing the stylus at different distances inwardly from the peripheral edge of a single record, whereby two, three or more separate and independent recordings may be made on the same disc, with said recordings starting and stopping within and covering predetermined concentric annular areas of the record, respectively, with blank rings therebetween, if desired. Such an application of the invention has special utility in the home for recording short songs, recitations and sayings of small children, for example, or for any other desired purpose.

The foregoing description, and the construction shown in the drawings, while disclosing a practical form of the invention, are provided for

illustrating the principles of the invention only, and are not to be considered as placing any limitations on the invention aside from the scope of the appended claims, as dictated by the prior art.

5. I claim:

1. In a phonograph apparatus employing a disc record and a stylus manually movable horizontally across and vertically with respect to said record from a rest position free of the record to an operating position in contact with the record, indexing means including one element connected to said stylus and controlled exclusively by said horizontal movement thereof, for indicating arrival of the stylus at a point in vertical registry with said operating position, and means including a member connected to said stylus and controlled exclusively by said vertical movement for cooperation with said element to effect the indication of arrival of the stylus at said point while the stylus is raised off the record and for rendering said indexing means ineffective when said stylus is lowered into contact with the record.

2. In a phonograph apparatus employing a disc record and a stylus manually movable horizontally across and vertically downward with respect to said record from a rest position free of the record to an operating position in contact with the record, indexing mechanism for establishing said contact at a predetermined point spaced inwardly from the peripheral edge of the record comprising means including one element connected to said stylus and movable through a predetermined path in response to horizontal movement of the stylus, and intercepting means including one member connected to said stylus and cooperative with said element of said first means and responsive to upward vertical movement of the stylus in conjunction with horizontal movement of the stylus to effect indexing of the stylus in alignment with said operating position and thereafter responsive to downward movement of the stylus to render said indexing mechanism ineffective.

3. In a phonograph apparatus employing a disc record and a stylus manually movable horizontally across and vertically with respect to said record from a rest position free of the record to an operating position in contact with the record, indexing mechanism for establishing said contact at a predetermined point spaced inwardly from the peripheral edge of the record comprising means including one element connected to said stylus and movable through a predetermined path in response to horizontal movement of the stylus and intercepting means including one member connected to said stylus and cooperative with said element of said first means and movable into and out of said path in response to vertical movement of the stylus.

4. In a phonograph apparatus employing a disc record and a stylus manually movable horizontally across and vertically with respect to said record from a rest position free of the record to an operating position in contact with the record, indexing mechanism for establishing said contact at a predetermined point spaced inwardly from the peripheral edge of the record comprising means including one element connected to said stylus and movable through a predetermined path in response to horizontal movement of the stylus and intercepting means including one member connected to said stylus and cooperative with said element of said first means and yieldably supported in said path.

5. In a phonograph apparatus employing a disc record and a stylus manually movable horizontally across and vertically with respect to said record from a rest position free of the record to an operating position in contact with the record, indexing means for establishing said contact at a predetermined point spaced inwardly from the peripheral edge of the record comprising means including one element movable through a predetermined path in response to horizontal movement of the stylus, intercepting means including one element in said path and cooperative with said first means, a yieldable support for one of said elements, and one of said elements including a plurality of position indicators engageable 15 consecutively with the other of said elements.

6. In a phonograph apparatus employing a disk record and a stylus manually movable horizontally across and vertically with respect to said record from a rest position free of the record to an operating position in contact with the record; indexing means including two independently movable cooperating stop members, means operatively connecting one of said members to said stylus to be responsive to said horizontal movement for indicating arrival of the stylus at a point in vertical registry with said operating position, and separate means operatively connecting the other of said members to said stylus to be responsive to said vertical movement for rendering said indexing means ineffective when said stylus is lowered into contact with the record.

7. In a phonograph apparatus employing a stylus, means including a pivoted arm for supporting said stylus and mounted for movement across and perpendicular to a record from a rest position to an operative position, indexing means remotely situated with respect to said stylus-supporting arm for stopping the movement of said supporting means across the record at predetermined points spaced from said rest position comprising an element in the form of a second arm movable in the record crossing direction with said stylus-supporting arm, a relatively fixed element, relatively spaced indentations on one of said elements, a detent on the other of said elements for engaging said indentations consecutively, and means comprising a train of component links and levers operatively connecting said stylus-supporting arm and one of said elements of said indexing means responsive to said perpendicular movement of the stylus-supporting means for effecting disengagement of the detent from any one of the indentations engaged thereby.

8. In a phonograph apparatus employing a stylus, means including a pivoted arm for supporting said stylus and mounted for movement across and perpendicular to a record from a rest position to an operative position, indexing means remotely situated with respect to said stylus-supporting arm for stopping the movement of said supporting means across the record at predetermined points spaced from said rest position comprising an element in the form of a second arm movable in the record crossing direction with said stylus supporting arm, a relatively fixed element, relatively spaced indentations arranged in a line on one of said elements, a detent on the other of said elements for interengagement with said indentations consecutively, and means comprising a train of component links and levers operatively connecting said stylus-supporting arm 75

and one of said elements of said indexing means responsive to said perpendicular movement of the stylus-supporting means for shifting one of said elements crosswise to said line for effecting alignment and disalignment of the detent and indentations.

9. In a phonograph apparatus employing a stylus, means pivotally supporting said stylus and mounted for movement across and perpendicular to a record from a rest position to an operative position, indexing means remotely situated with respect to said stylus-supporting arm for stopping the movement of said supporting means across the record at predetermined points comprising an element in the form of a second arm movable in the record crossing direction with said stylus-supporting arm, a relatively fixed element spaced from said rest position, relatively spaced indentations arranged in a line on one of said elements, a detent on the other of said elements for engaging said indentations consecutively, and means comprising a train of component links and levers operatively connecting said stylus-supporting arm and one of said elements of said indexing means operable by said perpendicular movement of the stylus-supporting means for shifting one of said element radially with respect to the pivotal axis of said stylus support across said line for effecting alignment and disalignment of the detent and indentations.

10. In a phonograph apparatus employing a stylus, means pivotally supporting said stylus and mounted for movement across and perpendicular to a record from a rest position to an operative position, indexing means for stopping the movement of said supporting means across the record at predetermined point spaced from said rest position comprising an element movable with said stylus-supporting means, a relatively fixed element, relatively spaced indentations on one of said elements, a detent on the other of said elements for engaging said indentations consecutively, means operable by said perpendicular movement of the stylus supporting means for shifting one of said elements radially with respect to the pivotal axis of said stylus supporting means comprising a rod engageable at one end with said supporting means, and means engageable with the opposite end of said rod for effecting said radial shifting movement of said one element and consequent alignment and disalignment of the detent and indentations.

11. In a phonograph apparatus employing a stylus, means pivotally supporting said stylus for movement inwardly across and perpendicular to a record from a rest position to an operative position, indexing means for stopping said movement at predetermined points spaced from said rest position comprising an element movable with said stylus, a relatively fixed element, relatively spaced indentation on one of said elements, a detent on the other of said elements for engagement with said indentations consecutively, means responsive to said perpendicular movement of the stylus support for shifting one of said elements radially with respect to the pivotal axis of said stylus support for effecting alignment and disalignment of the detent and indentations, comprising a rod engageable at one end with said support, and a bell-crank lever engageable with the opposite end of said rod and connected to the element adapted to be shifted.

12. In a recording apparatus for phonographs employing a groove-cutting stylus, means pivotally supporting said stylus for movement across

and perpendicular to a record from a rest position to an operative position, indexing means for stopping said movement at predetermined points spaced from said rest position, comprising an element movable with said stylus, a relatively fixed element, relatively spaced indentations on one of said elements, a detent on the other of said elements for engagement with said indentations consecutively, means responsive to said perpendicular movement of the stylus support for shifting one of said elements radially with respect to the pivotal axis of said stylus support for effecting alignment and disalignment of the detent and indentations, comprising a rod engageable at one end with said support, a bell-crank lever engageable with the opposite end of said rod and connected to said shiftable element, and resilient means for urging said radial movement in one direction.

13. In a recording apparatus for phonographs employing a stylus for cutting a sound groove in a record, a shaft, an arm secured to one end of the shaft and supporting the stylus for swinging movement over and perpendicular to the record from a rest position to an operative position, an index arm secured to the shaft for swinging movement concurrently with said stylus-supporting arm, a post radially disposed with respect to said shaft, an index bar radially disposed with respect to said shaft and said post and slidably supported at one end by said post, a bell-crank lever supporting and connected to said bar adjacent said shaft, a push rod coaxial with and axially slidable in said shaft with one end engaging said bell-crank lever and its opposite end engageable by said stylus-supporting arm, a detent carried by said bar adjacent said index arm, and a plurality of indentations in said index arm relatively spaced on an arc concentric to said shaft, said bar being shiftable radially with respect to said shaft and carrying said detent into and out of circular alignment with said arc in response to perpendicular movements of said stylus-supporting arm.

14. In a recording apparatus for phonographs employing a stylus movable from a position "off" a record to a position "on" the record manually and thereafter across the record under power to cut a sound groove therein, said apparatus comprising indexing means and driving means for the stylus including an element common to both said means, means operatively connecting said common element with said stylus for concurrent movement between said "on" and "off" positions of the stylus means engageable with said common element to indicate registry of the stylus with said "on" position, and means engageable with said common element for driving the stylus across the record.

15. In a recording apparatus for phonographs

employing a stylus movable from a position "off" a record to a position "on" the record manually and thereafter across the record under power to cut a sound groove therein, said apparatus comprising indexing means and driving means for the stylus including an element common to both said means, means operatively connecting said common element with said stylus for concurrent movement between said "on" and "off" positions of the stylus means engageable with said common element to indicate registry of the stylus with said "on" position, means engageable with said common element for driving the stylus across the record, and means for rendering said registering means ineffective during said driving.

16. In a recording apparatus for phonographs employing a stylus movable from a position "off" a record to a position "on" the record manually and thereafter across the record under power to cut a sound groove therein, said apparatus comprising indexing means and driving means for the stylus including an element common to both said means, means operatively connecting said common element with said stylus for concurrent movement between said "on" and "off" positions of the stylus means including an element engageable with said common element at one of a plurality of predetermined points on said common element to indicate registry of the stylus with said "on" position for one of a plurality of differently sized records, and means engageable with said common element for driving the stylus across the record.

17. In a recording apparatus for phonographs employing a stylus movable from a position "off" a record to a position "on" a record manually and thereafter across the record under power to cut a sound groove in the record, said apparatus comprising a pivoted arm for supporting said stylus, a second arm operatively connected to said stylus-supporting arm to pivot therewith, intercepting means in the path of said second arm to indicate arrival of the stylus at said "on" position, and rotary means engageable with said second arm to drive said stylus across the record.

18. In a recording apparatus for phonographs employing a stylus movable from a position "off" a record to a position "on" a record manually and thereafter across the record under power to cut a sound groove in the record, said apparatus comprising a pivoted arm for supporting said stylus, a second arm operatively connected to said stylus-supporting arm to pivot therewith, resilient intercepting means projecting into the path of said second arm to indicate arrival of the stylus at a plurality of "on" positions consecutively, and rotary means engageable with said second arm to drive said stylus across the record.

GILBERT G. BROWN.
